UNITED STATES PATENT OFFICE.

HENRY S. WHITE, OF CHICAGO, ILLINOIS.

ROTARY MOTOR.

Specification of Letters Patent.

Patented Apr. 25, 1916.

1,180,747.

Application filed December 26, 1905. Serial No. 293,387.

To all whom it may concern:

Be it known that I, HENRY S. WHITE, a subject of King Edward VII of Great Britain, residing at Chicago, in the county 5 of Cook and State of Illinois, have invented certain new and useful Improvements in Rotary Motors, of which the following is a specification.

This invention relates to improvements 10 applicable to all forms of rotary engines but more particularly to heat or gas motors.

The principal object of this invention is to embody in a mechanical form, far more effectively than is possible in any form of 15 reciprocating motors, the cycle of operations necessary to obtain from the combustion of any fuel within the working part of said motors the maximum possible result in useful work done.

20 Another object of this invention is the simplification to its utmost possible limits, both as to number and form, of the mechanical devices and operations necessary in the process of the transformation of heat into 25 work.

These objects can never be efficiently obtained in a motor in which the principal working parts are reciprocating and I have, therefore, endeavored to overcome as effectively as possible, the mechanical difficulties 30 in the way of obtaining the desired results in a machine in which the principal working parts are rotating instead of reciprocating.

Any of the cycles now carried out by reciprocating motors may be far more effectively carried out by my rotary motor, as will be fully shown and explained in the succeeding description of my invention.

Two main characteristic features differ- 40 entiate the cycles of operations of all existing reciprocating motors, namely, either the combustible is mixed with air before compression, or it is introduced into the air after it has been compressed and heated. 45 Far better results are obtained by the latter process than by the former in the reciprocating motor, and, of course, the same will hold equally true of the rotary motor. Incidentally also the latter process very largely 50 simplifies the mechanical devices necessary for putting it into operation. Therefore, preferably, the form every rotary motor would take would be one in which the air is compressed before the introduction of the combustible; and for this reason I have more 55 fully described and illustrated in this speci-

fication, this form of my motor than the form in which the cycle of operations begin by mixing the air and combustible before compression. At the same time, it must be understood that the invention covers one cycle as fully as the other, and that each cycle can be equally as efficiently carried out in my rotary motor and in each case far more efficiently than can ever be possible in a reciprocating motor.

The principal upon which the preferred cycle is based is that the number of heat units contained in any combustible are far too great to be wholly converted into useful work done, and that therefore the majority of these heat units are lost at the exhaust, and by absorption into a water jacket or other means of artificial cooling. Obviously this waste is avoided by introducing before combustion a large excess of air which absorbs the heat and transforms it into useful work done, instead of allowing it to be wasted at the exhaust or by a water-jacket.

I will now proceed to describe the manner in which the preferred cycle is mechanically carried out by my rotary engine, and have illustrated one form of my invention on the accompanying sheets of drawings forming a part of this specification in which:

Figure 1 is an elevation partly in section of one side of the motor; Fig. 2, is an edge view partly in section of the same; Fig. 3, 85 is an elevation partly in section of the side opposite to that shown in Fig. 1; Fig. 4, is an enlarged sectional view through the valves and Fig. 5, is a section on line 5—5 of Fig. 4.

95 Similar reference characters refer to similar parts throughout the several views.

The stationary part of the motor is preferably made up of three separate castings so formed that when bolted or otherwise secured together they form a solid casing containing two concentric annular chambers 7 and 8 which are shown as being circular but may be of any desired shape in cross section; 7 is the expansion chamber and 8 is the compression chamber.

Piercing the casing 6 axially is the driving shaft 9 suitably journaled in the casing or otherwise upon which are keyed or otherwise secured, the revolving disks 10 and 11 carrying on their peripheral edges the pistons 12 and 13 arranged to move in the an-

nular chambers 7 and 8 respectively. The two annular chambers 7 and 8 need not necessarily be of equal diameter nor be disposed at equal distances radially from the center of the driving shaft, as shown. These details of construction will depend upon the varying conditions of work to be done by different motors.

The passageway 14 which is provided with a valve 15, preferably a balanced valve, forms means of communication between the expansion chamber 7 and compression chamber 8. There may be one or more passages 14, as desired, in a single motor, I have shown two such passages arranged diametrically opposite to each other and therefore two pistons 12 and two pistons 13 but will describe and refer to only one with its co-operating parts, it being understood that they are both alike, and both with their co-operating parts have the same effect on the pistons 12 and 13.

The valve 15 is normally held closed by a spring 16 and is positively opened at the proper time by being connected to the sliding rod 17 by means of the duplex levers 18; the rod 17 being provided with a friction roller to travel on the surface of the cam 19 secured to the driving shaft 9, and provided with the raised portion 20. As the shaft 9 is rotated and the raised portion 20 passes under the friction roller the rod 17 will be shifted to open valve 15, and permit free communication between the chambers 7 and 8.

To admit or force combustible fluid into the expansion chamber 7 a needle valve 21 is provided adjacent the valve 15 having its exposed stem provided with a cross arm or pin 22 arranged to extend into the slots 23 of the forked lever 24. One end of the lever 24 is pivoted at 25 to an arm extending from the frame 6, and the other end is connected to the sliding rod 26 provided with a friction roller to engage the disk 27 provided with the adjustable cam 28 in such manner that as the friction roller is engaged by the cam 28 the valve 21 will be opened and admit the combustible fluid which enters the valve through the pipe 29 into the expansion chamber 7. The rod 26 is mounted to slide in a guide bracket, 30 extending from the frame 6, and a coiled expanding spring 31 is interposed between the bracket 30 and a collar 32 secured on the rod 26 to normally hold the valve 21 in a closed position.

As the pistons 12 and 13 pass around in their respective chambers in the direction indicated by the arrows in Figs. 1 and 3 the two being separated by only a short distance circumferentially, the piston 12 approaches the valve 33 in chamber 7 and piston 13 approaches valve 34 in chamber 8. While the pistons are thus approaching the valves, valve 33 is open and valve 34 is closed and

results in compressing the air in chamber 8 from the time that piston 13 has passed the port 35, the compressing continuing until valve 15 is opened, which occurs immediately after piston 12 has passed valve 33 and said valve 33 is closed. The opening of valve 15 permits the greatly compressed air to pass from chamber 8 into chamber 7 and at once closes. The instant valve 15 is closed, needle valve 21 is opened and any oil as gasoline is forced under pressure into chamber 7 and mixed with the compressed air. The air by reason of its quick compression has been raised to a temperature higher than the temperature of ignition of the fuel which will ignite as soon as it is introduced into chamber 7 and the expansion during its combustion will force the piston 12 around in the direction indicated by the arrow in Fig. 1. The products of combustion are expelled from the chamber 7 by piston 12 during the time it is approaching valve 33 through the exhaust port 36.

The valves 33 and 34 may be of any desired construction but I prefer to make them cylindrical and provide each with a perforation to register with the chamber 7 and 8 respectively when the valves are open. The pistons 12 and 13 pass through these perforations in their respective valves in their passage around in the chambers 7 and 8, and to accommodate the passage of a portion of the peripheral edges of the disks 10 and 11 a slot 37 is provided in each valve 33 and 34. The pistons may be secured to the disks 10 and 11 by an extension 38 provided on each disk extending into a recess provided therefor in each piston.

The valves 33 and 34 are opened and closed by partially rotating them through connections with the driving shaft 9. Valve 33 has secured to the exposed end of its stem 39 a crank arm 40, provided with a pin 41 engaged by the forked end of a bell crank 42 pivoted to the casing 6 at 43. The other arm of the bell crank is provided with a friction roller 44 arranged to engage the disk 45 secured on shaft 9 and provided with the cam surface 46 in such manner that valve 33 will be open when the roller 44 is traveling over the cam surface 46. The valve 33 is normally forced to a closed position by a constant pull exerted by a spring or dashpot 47.

The valve 34 has secured to the exposed end of its stem 48 a crank arm 49 provided with a pin 50 which is engaged by the forked end of one arm of a bell crank 51 pivoted to the casing 6 at 52. The other arm of the bell crank 51 is made in the shape of a pawl 55 to engage the periphery of the disk 53 secured on the shaft 9 and provided with the cam surface 54 in such manner that valve 34 will be open when the pawl 55 is in engagement with the cam surface 54. The

valve 34 is normally held in an open position by a constant pull exerted by a spring or dash-pot 56.

The rod 17 is arranged to slide in the 5 guide bracket 57 extending from the casing 6. The cams 28 are pivotally mounted on the disk 27 on the pins 58 in such manner that the portion which is contacted by the friction roller on the slide rod 26 can be 10 increased or decreased in extent by swinging the cam 28 about the pivot 58.

When the portion of the cam 28 affecting the slide rod 26 is increased in extent the amount of fuel fed into chamber 7 is increased 15 proportionately and when such portion of cam 28 is decreased the amount of fuel fed into chamber 7 is proportionately decreased. To effect an automatic feeding of the fuel into the chamber 7 a weight 59 is adjustably secured to the cam 28 in such manner that when the weight 59 is forced away from the shaft 9 by centrifugal force the cam 28 will be 20 swung about the pivot 58 so as to reduce the amount of fuel fed into chamber 7 and when the speed of the shaft decreases and allows the weight 59 to be drawn back toward the shaft 9 by the spring 60 on account of the reduced centrifugal force affecting 25 such weight, the cam 28 will be moved about pivot 58 so as to feed more fuel into the chamber 7. It will be seen that this arrangement of the cam 28 and weight 59 acts as a governor, regulating the 30 speed of the motor. Any convenient positive stop is provided for the weight 59, as the disk 61 secured to the shaft 9. When two or more cams 28 are provided on the motor they are preferably connected by 35 links 62 or other means to compel them to move simultaneously.

Any desired means for packing the motor may be used but I have shown spring rings 40 on the pistons 12 and 13 and U-shaped annular packing rings 63 on either side of the peripheral edge of each disk 10 and 11. A short distance from the peripheral edge of each disk and on either side 45 10 and 11 are oil grooves 64, and still farther toward the shaft 9 on either side of each disk are the grooves 65 which contain packing to 50 prevent the oil from grooves 64 working toward the shaft 9.

It will be understood that numerous and 55 in some cases very radical changes can be made in the construction of the motor and parts without in the least departing from the spirit of the invention.

To carry out the cycle of the motor as 60 described effectually the air must have been compressed at least sufficiently to have raised its temperature higher than the temperature of ignition of the fuel, and for reasons well known to those who have a knowledge 65 of thermodynamics, to obtain a high

thermal efficiency, the compression should be continued at least to a point as high as is possible without injury to the material of which the motor and its parts are composed; which would be a temperature very 70 much higher than the temperature of ignition of any liquid fuel, thus immediately upon entering this highly compressed air the fuel ignites.

The fuel oil is forced through the pipe 75 29 by a force pump not shown, and preferably driven by the shaft 9. As the pistons revolve that fuel continues to enter gradually and be immediately ignited. This process is however so gradual that it does 80 not raise the temperature of the compressed air but only maintains it at its initial highest temperature; the added temperature of combustion equaling but not exceeding the loss of temperature, due to expansion, thus 85 there is a period of isothermal expansion while the fuel continues to be admitted.

The period of admission will depend upon the degree of compression but should be so proportioned that when the motor stroke 90 is completed the air and the products of combustion have been expanded as nearly as possible to atmospheric pressure at the time they start to exhaust, thus being of a temperature not much higher than the temperature 95 of the air previous to compression.

If two such pairs of annular chambers as are shown in the drawings should be arranged upon the driving shaft in such a manner that the pistons of the respective 100 pairs alternate with each other there will be no point in the cycle during which there is no energy exerted to rotate the driving shaft, thus there would be no necessity of a fly wheel. Furthermore it will be seen that 105 no artificial means of ignition is required, neither will there be any necessity of cooling the walls of the combustion chambers, thus eliminating all such devices as the sparkler, carburetor and water jacket. 110

A motor in which an explosive mixture is drawn into the compression chamber instead of pure air would be considered as a modification of my invention so long as the principles of construction and operation as 115 described are retained. In such a modification it would be necessary to provide an igniter in the expansion chamber.

By the use of my invention it is possible to proportion the volume compressed and 120 the volume expanded to any desired ratio, this being conveniently accomplished by making the diameters of the two chambers differ in proportion to the ratio desired.

Any convenient means can be provided to 125 give the motor one revolution in order to start it. When it is desired to stop the motor the fuel supply is shunt off; this can easily be done in the construction shown in the drawings by taking hold of the handle 130

66 provided on the stem of valve 21 and turning said valve a one quarter revolution, which brings the pin or cross arm 22 in a position to register with the horizontal slot 5 of the forked lever 24 and said valve stem will therefore not be moved by the lever 24, thus shutting off all supply of fuel through needle valve 21.

In small motors of low power in which 10 simplicity of construction would be more an object than economy of fuel or thermal efficiency, a still further modification of the cycle in this motor would be to dispense with compression altogether. The motor would 15 then consist of one annular expansion chamber only.

Having thus fully described my invention what I claim as new and desire to secure by Letters Patent of the United States is:—

- 20 1. In a motor, a suitable frame, two inclosed annular chambers in said frame circular in cross section, a compression piston arranged to move in one of said annular chambers, a working piston arranged to move in the other of said annular chambers, a passageway controlled by a valve forming communication between said two annular chambers, a valve in each annular chamber to serve as an abutment and means whereby an explosive mixture is automatically introduced between said two pistons and ignited by the action of said compression piston.
- 25 2. In a rotary motor, the combination of an inclosed annular chamber to form a charging chamber, a piston to move in said

charging chamber, a second inclosed annular chamber to form a power chamber, a piston to move in said power chamber, a short connecting passage or port between 40 said two chambers controlled by a valve, and means whereby the said two pistons move in unison in their respective chambers, so that during the period of the transfer of the charge, after compression, from 45 the charging chamber to the power chamber said charge remains at constant or approximately constant volume.

3. In a motor, a suitable frame, an inclosed annular chamber in said frame, a piston arranged to move in said annular chamber, an abutment in said chamber arranged to be moved to allow said piston to pass, a valve for the admission of fuel into said annular chamber, a shaft to which said piston is secured, a cam mounted to swing on a pivot secured to said shaft controlling the action of said valve, and a weighted adjustable section mounted on said cam whereby the fuel is automatically admitted into said 60 chamber and controlled by the speed of the motor by the centrifugal force exerted upon said weighted section.

In testimony whereof I have signed my name to this specification in presence of two 65 subscribing witnesses this 19th day of December, 1905, at Chicago, Ill.

HENRY S. WHITE.
